STOKER DRIVE

William W. Peck, Muncie, Ind.

Application July 14, 1934, Serial No. 735,164

3 Claims. (Cl. 74—124)

My invention relates to improvements in mechanically driven furnace stokers, primarily designed for small heating plants such as are used for heating dwellings and the like.

More particularly my invention relates to the drive mechanism for the fuel feeding device and one of the objects of my invention is to provide a drive which shall be extremely efficient in operation, which may be cheaply manufactured, and which is extremely silent in operation.

Another object of my invention is to provide means whereby a device having the above characteristics may be regulated to vary the quantity of fuel fed at a given time irrespective of the speed of the driving member therefor.

For the purpose of disclosing my invention I have illustrated an embodiment thereof in the accompanying drawings in which

Fig. 1 is a side elevation, more or less diagrammatically illustrating a stoker embodying my invention;

Fig. 2 is an end view thereof;

Fig. 3 is a sectional view taken on the line 3—3 of Fig. 4;

Fig. 4 is a sectional view taken on the line 4—4 of Fig. 2;

Fig. 5 is a detail of the ratchet driving mechanism with means for adjusting its stroke, and

Figs. 6 and 7 are respectively end and side elevations, partly in section, of a clutch interposed between the power member and the drive.

In the embodiment of the invention illustrated the stoker mechanism comprises the usual burner 1, which is fed through a feed 2 by means of a feed screw from a hopper 3. It will be noted that the hopper is set at an incline so that there will always be a tendency for the coal therein to slide toward the bottom of the hopper and into the feeding screw. By such an inclination the danger of the fuel in the hopper "bridging" is eliminated. The feeding mechanism is driven from preferably an electric motor 4 through the instrumentality of a transmission 5, a slip clutch 6 being preferably interposed between the motor 4 and the transmission to permit a slip between the motor and the driving mechanism in event the feed mechanism becomes jammed for any reason.

The transmission mechanism is preferably mounted within a casing 7 having a flat base 8 on which it is supported and provided with a removable cover 9. Extending into this casing is a drive shaft 10 which, if desired, may project beyond the two side walls of the casing to provide, at one end, a connection for the driving motor 4 and at the other end a means for driving

a suitable blower 11. The shaft 10 is preferably mounted in ball bearings such as 10a arranged in the walls of the casing and these bearings provide end thrust bearings as well as side bearings for the shaft. The shaft 10 is provided with a worm 12 which is preferably formed integrally with the shaft. Extending transversely of the shaft 10, which may be termed the driving shaft, is a driven shaft 13 one end of which is adapted to be connected with the feeding screw 14 of the fuel feed. This shaft is likewise mounted in ball bearings 15 arranged in the side walls of the casing and constituting end as well as side thrust bearings. Rotatably mounted on the shaft 13 is a worm gear 16 meshing with the worm 12 and 15 driven thereby. The hub of this worm gear 16 is provided with a cam member having two cam portions 17 and 18 adapted during the rotation of the gear 16 to oscillate the cam arm 19. This cam arm is mounted on a transversely extending shaft 20 and has somewhat the shape of a bell crank lever, the extension 21 of which is provided with a pair of pivoted dogs 22 and 23. A ratchet wheel 24 is keyed on the shaft 13 and the dogs or pawls 22 and 23 are adapted to engage the teeth 25 of the ratchet wheel for rotating the same in one direction. Due to the fact that one of the dogs, 23, is slightly longer than the other dog 22, engagement of the dogs with the teeth of the ratchet wheel is insured, even though the oscillations of the arm 21 may be very slight. A backlash dog 25 rockably mounted on the shaft 20 also engages the teeth of the ratchet wheel to hold the same against backward movement.

For adjusting the throw of the arm 19 I provide an adjustment member comprising a lever arm 26 having a hub 27 surrounding the shaft 20. This hub is provided with relatively large keyways 28 into which take keys 29 on the shaft 20. These keyways in effect form stops for limiting the movement of the shaft 20 and with it the movement of the arm 19, this arm being fixed on the shaft 20 which, in itself is rotatably mounted. The lower end of the arm 26 is provided with a pin 30 adapted to take into spaced apart openings 31 in the side of the casing, and the arm is maintained with the pin engaged in a selected opening through the medium of a coiled spring 32 surrounding the shaft and abutting against a shoulder 33 on the hub 27 and a collar 34 on the shaft. It is apparent that by shifting the arm 26 to the left, looking at Fig. 2 or Fig. 5, and raising the arm 19 so that the cam will not engage the same until it has completed part of its stroke, the length of the stroke of the arm 19

and correspondingly the length of the stroke of the pawls 22 and 23 may be varied to control the rate of feed of the fuel.

In apparatus of this character there is danger of the screw 14 becoming jammed during the feeding of the fuel, for various reasons, and in order to prevent the stoppage of the motor 4 by the jamming of the screw and therefore the burning out of the motor, I provide a simplified form 10 of clutch which is preferably interposed between the shaft 10 and the shaft 35 of the motor drive. This clutch preferably comprises a housing member 36 keyed on the shaft 10 and having a rim 37. Keyed on the shaft 35 are a pair of arms 15 38 operating between the adjacent ends 39 of a pair of shoes 40, which shoes bear on the inner periphery of the rim 37. These shoes are preferably maintained in engagement with the rim 37 by coiled springs 41 between the ends of the 20 shoes, which springs preferably extend through the arms 38 without touching the arms. By this arrangement the clutch provides a self-aligning connection between the motor and the drive mechanism. It is apparent that when the arms 25 38 are rotated they will come in contact with the abutting ends of the shoes 39 and due to the combined action of the springs 41 and centrifugal action these shoes will be maintained in frictional engagement with the rim 37, whereby friction 30 drive will be established between the shaft 35 and the shaft 10.

I have found that the above construction provides an extremely silent drive and I have found that this silence is materially assisted by so arranging the arm 19 that during the return movement of its stroke it does not come in actual contact with the cams 17 and 18.

I claim as my invention:

1. In a stoker drive, in combination, a casing, 40 a drive shaft extending into said casing, a worm pinion mounted on said drive shaft, a driven shaft extending into said casing, a worm gear rotatably mounted on said driven shaft, and meshing with said pinion, a cam member operably connected 45 to and rotated by said worm gear, a ratchet gear fixed on said driven shaft, an oscillating arm shaft, an oscillating arm oscillated by engage-

ment with said cam member, a stop member on said oscillating arm shaft and a second stop member on said cam arm to limit the return movement of said cam arm, means for adjustably rotating said oscillating arm shaft to adjust the 5 relative positions of said stops and pawls pivoted on said oscillating arm and adapted to engage the ratchet teeth on said ratchet gear during the positive movement of said arm under the action of said cam. 10

2. In a stoker drive, in combination, a casing, a drive shaft extending into said casing, a worm pinion mounted on said drive shaft, a driven shaft extending into said casing, a worm gear rotatably mounted on said driven shaft, meshing 15 with said pinion, a cam member operably connected to and rotated by said worm gear, a bell crank lever shaft, a bell crank loosely mounted on said shaft, one of the arms of said bell crank to be biased into engagement with said cam 20 member and the other arm having pawls pivoted thereon for engagement with the ratchet teeth of said ratchet gear, a key on said bell crank lever shaft, and a key way in the hub of said bell crank lever shaft of greater width than said key, and 25 means for rotatably adjusting said bell crank lever shaft.

3. In a stoker drive, in combination, a drive shaft, a driven shaft, constant mesh reduction gear members, one fixed to said drive shaft, a cam member fixed relative to the other and slower speed reduction gear member, a one-way intermittent drive assembly including a driven part fixed to said driven shaft and a drive part, 30 an oscillatable arm shaft, an arm carried on said 35 arm shaft and mounted for limited rotation relative thereto, said drive part being mounted on said arm and operatively engageable with said driven part, said arm being adapted to engage with said cam member, a stop member on said 40 oscillating arm shaft, and a second stop member on said cam-engaging arm to limit the return movement of said arm in the direction of said cam, and means for adjustably rotating said oscillating arm shaft to adjust the relative positions 45 of said stops.

WILLIAM W. PECK.
